UPHOLSTERED SEAT

Victorio Introini, Gallarate, Italy, assignor to Fratelli
Saporiti, Besnate, Parese, Italy

Filed Mar. 18, 1974, Ser. No. 452,412

Term of patent 14 years

Int. Cl. D6—01

U.S. Cl. D6—71

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 14.

FIG. 15.

FIG. 16.

FIG. 17.

FIG. 18.

FIG. 19.

FIG. 1 is a perspective view of a seat in the form of a chair embodying the present design;

FIG. 2 is a front elevational view thereof;

FIG. 3 is a side looking from the left of FIG. 2;

FIG. 4 is a side view looking from the right of FIG. 2;

FIG. 5 is a top plan view thereof;

FIG. 6 is a bottom view;

FIG. 7 is a rear view;

FIG. 8 is a view similar to FIG. 2 showing a seat embodying the present invention in the form of a modified chair;

FIG. 9 is a front perspective view of the FIG. 8 embodiment;

FIG. 10 is a side view looking from the left of FIG. 8;

FIG. 11 is a perspective view of a seat embodying the present invention in the form of a love seat;

FIG. 12 is a side view looking from the right of FIG. 11;

FIG. 13 is a front elevational view of the FIG. 11 embodiment;

FIG. 14 is a front elevational view of a seat embodying the present invention in the form of a modified love seat;

FIG. 15 is a perspective view of the love seat of FIG. 14;

FIG. 16 is a side view looking from the left of FIG. 14;

FIG. 17 is a perspective view of a seat embodying the present invention in the form of a sofa;

FIG. 18 is a side view of the sofa of FIG. 17 looking from the left thereof; and

FIG. 19 is a front elevational view of the sofa of FIG. 17.

I claim:

The ornamental design for an upholstered seat, as shown.
